J. B. GLOWACKI

FUSE PLUG, SCREW TYPE, WITH INDICATOR

Original Filed May 15, 1922

UNITED STATES PATENT OFFICE.

JOHN B. GLOWACKI, OF CHICAGO, ILLINOIS.

FUSE PLUG, SCREW TYPE, WITH INDICATOR.

Application filed May 15, 1922, Serial No. 560,916. Renewed December 8, 1926.

This invention relates to that type of renewable fuses which are adapted to screw into a socket similar to a lamp socket and are known as fuse plugs.

5 It is an object of this invention to provide such a fuse plug with an indicator which shall clearly and readily show which of a collection of fuse plugs has been blown.

10 It is a further object of this invention to provide a detachable mounting for a fuse strip of a type that may be easily and quickly inserted in a fuse plug and in which the fuse strip may be very readily renewed without the need of any special tools.

15 It is a further object of this invention to provide a fuse plug of a type which shall afford an abundant outlet for the products of the explosion when the fuse is blown and yet which shall not be likely to set fire to 20 the surroundings.

It is a further object of this invention to provide a tortuous and narrow passage which shall relieve the explosion but shall not permit the flame to emerge.

25 It is a further object of this invention to provide the top of the fuse plug with an indicator which shall by its color or condition show when the fuse has been blown.

It is a further object of this invention to 30 make a fuse plug of the type described which shall be simple and compact in structure and neat in appearance.

Other and further important objects of 35 the invention will be apparent from the disclosures in the drawings and specification.

The invention (in a preferred form) is illustrated on the drawings and hereinafter more fully described.

On the drawings:

40 Figure 1 is a side elevation of the fuse plug.

Figure 2 is a central vertical section through the plug.

45 Figure 3 is a bottom plan view upon an enlarged scale of the fuse carrier.

Figure 4 is a side elevation of the fuse carrier.

Figure 5 is an edge view of the closure plate for the fuse carrier.

50 Figure 6 is an edge view of the fuse.

Figure 7 is a top plan view of the fuse carrier with the fuse and closure plate in position.

Figure 8 is a bottom plan view of the

head of the plug with the shell and spacing plate in place.

Figure 9 is a bottom plan view of the completed plug.

Figure 10 is a section through the spacing plate.

Figure 11 is a section upon an enlarged scale through the lower end of the fuse carrier.

Figure 12 is a section upon the line 12—12 of Fig. 4.

Figure 13 is a section upon an enlarged scale of the upper part of the plug in a plane at right angles to the section of Figure 2, the indicator being removed.

As shown on the drawings:

The plug comprises a fuse carrier 1 and a head 2, both made of insulating material. The fuse carrier is screwed into the interior of a screw-threaded shell 3 and the head 2 is screwed onto the exterior of the same shell, the head being screwed onto the shell at one end and the carrier screwed into the shell at the other end.

The carrier 1 is made of insulating material in the shape of a hollow cylinder having a lower end wall 4 which is provided with a circular recess 5 preferably having a beveled edge. The central part of the recess 5 contains a circular depression 6 in which is formed a rectangular depression 7, the corners of which extend beyond the circumference of the depression 6.

At the center of the rectangle 7 the depression is crossed by a slot 8 which pierces the wall 4 of the container 1. The interior of the container is a straight cylindrical hollow except that near its upper end it is provided with a shoulder 9 to afford a seat for a metallic closure plate 10.

At two diametrically opposite points the cylindrical wall is cut away down to the level of the shoulder as shown at 11 to provide for the passage of ears 12 upon the closure plate 10. Beyond these notches 11 the ears 12 are turned down into recesses 13 provided in the outer surface of the cylindrical wall of the holder 1.

The outer surface of the holder 1 is not uniform but the portion nearest the notches 13 is of smaller diameter to afford a space 15 within the screw-shaped shell 3 where the cylindrical carrier 1 stands away from the screw-threaded shell.

The middle part of the outer surface of the cylindrical carrier

is screw-threaded as shown at 16 to fit the screw thread of the shell 3; and the lower part of the carrier is knurled as shown at 17 to facilitate the screwing of the carrier into the shell.

The strip 18 of fusible metal is provided with narrowed places 19 to localize the heating. One end of the strip 18 is folded at a right angle as shown at 20 and then folded 10 through 180 degrees so that it projects in the opposite direction as shown at 21. The part beyond the last fold extends beyond the unfolded portion of the strip and is expanded into a circular member as shown in 15 Figure 9 at 22. When inserting the fuse into the fuse carrier the straight portion 18 is passed through the slot 8 so that the portion 20 comes to lie in one half of the rectangle 7, and the portion 22 fills the circular depression 6. The closure plate 10 is then inserted in place and the slot 23 therein receives the other end of the strip 18. This end is then bent flat against the outer face of the closure plate 10, as shown at 20 24 in Figure 13. The fuse carrier and its fuse are then ready to be screwed into the shell 3.

Before the shell receives the fuse carrier its spacing plate 25 is inserted in the shell. 30 As shown most clearly in Figure 13, the shell consists of a screw-threaded side wall, generally cylindrical in character, and an end 26. This end is provided with a central opening 27 opposite the middle of the spacing plate 25, but not in contact therewith because the plate 25 has an upstanding flange 28 which provides a distance between the surface of the plate and the surface of the end 26 of the shell. The other side of the 35 plate has a raised middle portion as shown at 29 which contacts with the turned over end 24 of the fuse strip 18. The spacing plate 25 is provided with holes 30 which connect the space into which the hole 27 opens 40 with the space 15 made by reducing the diameter of the fuse carrier 1. This space 15 is connected with the interior of the fuse carrier by orifices 32 shown most clearly in Figure 12.

50 The head 2 is traversed by a passage leading to the hole 27 and this passage is screw-threaded for the reception of an insulating tube 33 which is shown in section in Figure 2. The lower end of the tube is threaded 55 to fit the threads in the passage 27. The screw-threaded portion is separated from the rest of the tube by a flange 34 which fits into a recess 35 in the top of the head 2. The upper end of the tube is closed by an 60 end wall. In the illustration chosen this end wall is shown as dome-shaped, but this is not necessary. A little way below the end the tube has lateral openings 36 and just 65 below the openings 36 is a shoulder so that the upper end of the tube is of slightly

smaller diameter than the part just above the flange.

A cover 37, preferably of gelatine or other light and transparent material, is fitted over the tube 33. The lower end of this cover fits 70 the tube 33 and abuts against the flange 34. The part of the cover above the shoulder is spaced away from the smaller part of the tube and so affords a space into which the openings 36 lead. At the upper end of the 75 cover a small perforation is provided as shown at 38. A communication exists between the interior of the fuse carrier 1 and the outside atmosphere. This communication is through the holes 32 into the space 80 15, through the holes 30 into the upper part of the plate 25, through the hole 27 into the tube 33, and through the holes 36 into the interior of the cover 37; and finally through the hole 38 to the outside atmosphere. The 85 cover 37 may of course be omitted and the same venting action attained.

In assembling the device, the plate 25 is first placed inside of the shell 3 with the flange 28 against the end of the shell. A 90 pin prick or other depression is then made in the side wall of the shell 3, as shown at 40, to retain the plate 25 in position. The closed end of the shell 3 and a portion of the threaded sides of the shell adjacent thereto 95 are then coated with cement and screwed into the head 2. The fuse 18 is then inserted into the container 1 through the slot 8, as already explained. The closure plate 10 is passed over the other end of the fuse 100 18 with the ears 12 entering the recesses 13 and the protruding end of the fuse 18 is bent over against the plate 10 as shown in Figure 7. The fuse carrier 1 with the fuse 105 therein is then screwed into the shell 3 and the end 18 of the fuse contacts with the raised part 29 of the plate 25. The tube 33 is then screwed or otherwise permanently secured into the opening in the end of a base of the head 2 so that the flange 34 comes 110 into the recess 35. The cover 37 is then placed over the tube 33 and the lower edge of the cover contacts with the flange 34. Preferably the cover is wet just before being placed on the tube so that it will adhere 115 to the tube around the lower edge of the cover.

The fuse plug is then ready for use. It is screwed into a suitable socket, similar to a lamp socket. The screw threaded part of the socket contacts with the shell 3 and makes one terminal of the circuit. The central contact of the socket contacts with the end 22 and forms the other connection to the fuse strip 18. For this reason, the depression 5 is made no deeper than the height of the central projecting contact in a socket so that contact is always secured between the end 22 and this part of the socket. When the current is turned on it flows through 120 125 130

the shell 3 to the plate 25, through the elevated part 29 to the end 24 of the fuse, through the fuse to the end 22, and so to the other terminal in the socket.

5 When the current becomes excessive the fuse melts and if the excess is sudden and large the fuse may even vaporize suddenly enough to produce an explosion. The products of the explosion pass out of the interior of the container 1 through the holes 32 into the space 15. Emerging from the comparatively small holes 32 into the roomier space 15 checks the velocity of these products. They then pass through the holes 30 which emerge into the space above the plate 25. Here again the emerging from a hole into a larger space, accompanied by change of direction, checks the velocity of these products. The products then pass up the tube 33, suffer another change of direction to emerge through the hole 36, and finally come out into the interior of the cap 37. If there was but little force to the explosion the velocity of the products of the explosion will 25 have largely disappeared by the time this travel is accomplished and they will emerge through the hole 38 in the form of a slow line of smoke. If however the velocity is greater there may be force enough to break or displace the cap 37. Even when the cap is not broken or displaced the fumes from the explosion will discolor it so that the presence of the fumes is readily recognized. Even with explosions of considerable violence the many changes of direction and the frequent emerging from holes into roomier spaces check the outflow so effectively that no actual flame reaches the outside of the plug.

35 40 When the failure of light in the house or other occurrence makes the user of the device aware that a fuse has blown and he goes to the fuse box to inspect the same, the thin thread of smoke emerging through the hole 38 in the case of the fuse that has blown enables him to quickly locate said fuse; or if the observer arrives at the fuse box too late to see this he can observe which cap 37 is discolored or broken, or displaced, and thus readily identify the fuse that was blown. He then unscrews the fuse from the plug, unscrews the fuse container from the cap 2, removes the remaining portions of the strip 18 and inserts a new strip in the way 45 described, then screws the container back into the shell 3 and the plug back into the socket. The whole of this operation takes but a few seconds as compared with the many minutes usually used to replace a fuse 50 wire.

I am aware that numerous details of construction may be varied through a wide range without departing from the principles of this invention, and I therefore do

not purpose limiting the patent granted 65 otherwise than necessitated by the prior art.

I claim as my invention:

1. A screw-threaded shell, a dished plate secured in one end thereof, said plate having holes therethrough, a fuse container screwed 70 in said shell, a fuse in said container, said container having holes communicating with the interior of said shell on one side of said plate, and a head screwed on said shell, said head having a passage therethrough communicating with the other side of said plate. 75

2. In a fuse plug, a hollow cylinder, a closure plate at one end of said cylinder, said plate having a slot therethrough, a wall integral with said cylinder situated at the opposite end of said closure plate, said wall having a central slot therethrough and a depression on the exterior immediately surrounding said slot, a fuse in said plug extending through said cylinder with one end 80 projecting through said slot in said closure plate and the other end projecting through said slot in said wall, and a head on said fuse occupying said depression. 85

3. In a fuse plug, a hollow cylinder, a 90 fusible element mounted in said cylinder, a shell on the outside of said cylinder, a head removably secured on one end of said shell, a tortuous outlet from the interior of said cylinder to the outside of said head, and a 95 transparent apertured cap positioned over said outlet.

4. In a fuse plug, a hollow cylinder, a screw-threaded shell on the outside of said cylinder to engage within a socket, a head 100 secured on one end of said shell, a dished plate secured in one end of said shell and having a plurality of holes therethrough, a closure plate removably secured to one end of said cylinder, said plate having a slot therethrough, a wall integral with said cylinder oppositely positioned to said closure plate, said wall having a slot therethrough and a depression immediately surrounding the exterior of said last mentioned slot, a fuse extending through said last mentioned slot, the interior of said cylinder, and the slot in said closure plate, said fuse being bent over after 105 extending through said last mentioned slot and frictionally held between said closure plate and said dished plate, a head on said fuse occupying said depression, said cylinder having a plurality of holes therethrough, said head having a hole therethrough, a transparent apertured cap centrally positioned 110 over said head comprising an insulating tube closed at one end, said tube being threaded to fit said hole and having lateral openings, a transparent cover for said tube. 115

In testimony whereof I have hereunto subscribed my name. 120 125

JOHN B. GLOWACKI.
